CLOSURE

George Goebel, Baltimore, Md., assignor to Crown Cork & Seal Company, Inc., Baltimore, Md., a corporation of New York

Application May 23, 1934, Serial No. 727,182

2 Claims. (Cl. 215—43)

The present invention relates to caps and more particularly to a two-part screw cap for bottles, jars, and the like.

An essential feature of the invention resides in 5 a cap of this type having (1) an outer shell which is smooth and continuous; (2) an inner shell or member having thread engaging portions completely enclosed in said outer shell and provided with a screw thread; (3) the two shells 10 connected at their lower ends so that they will will not rotate with respect to each other, nor distort when the cap is turned on a container.

The inner shell has its lower edge outwardly folded and flattened against the skirt to form a 15 strengthening hem. This hemmed edge is roughened or provided with an irregular contact surface preferably upon each side.

The free edge of the outer shell is curled inwardly to embrace and engage the roughened 20 hemmed edge of the inner shell to fixedly associate the two shells, whereby when the shells are assembled and the cap is turned on a container, the shells will not rotate relative to each other.

Other objects and advantages of the invention 25 will become apparent from the following description when taken in conjunction with the accompanying claims and drawing.

Referring to the drawing in which is disclosed a preferred embodiment of the invention:

30 Figure 1 is a side elevation of a two-piece cap made in accordance with the invention showing the smooth continuous exterior.

Figure 2 is an enlarged cross-sectional view of the cap of Figure 1.

35 Figure 3 is an enlarged detailed section of the means for securing the shells together against relative rotation when the cap is turned.

Referring to the drawing in which like numerals indicate like parts in the several views, 10 designates as a whole, a two-piece metallic cap for 40 use as a closure on containers, such as bottles, jars, and the like.

The cap 10 comprises a preformed inner shell or member 11 having a top preferably formed 45 with a circular medially raised flat portion 12 connected to the outer marginal or depressed portion 13 by a circumferentially inclined portion 14. The inner member has a metallic skirt 15, knurled as at 15', and spirally threaded or grooved 50 below the knurling as at 16 so as to detachably connect the cap to a container having a threaded finish. The skirt 15 has an outwardly flared portion 17 which terminates in the free end 18, as shown in Figures 2 and 3. The free end 18 is 55 spaced from the adjacent wall of the container

when the cap is applied thereto and forms an enlarged entrant portion. The end 18 is preferably folded outwardly, as at 19, and the folded portion flattened upon the skirt to form the flat doubled wall or hemmed edge 20. The double 5 wall or hemmed edge 20 acts to strengthen and rigidify the cap.

The flattened or hemmed edge 20 has its surfaces roughened preferably upon each side, i. e., 10 interiorly and exteriorly of the inner shell as at 21, and as shown in Figure 2. The roughening may be produced in any suitable manner as by vertically corrugating or indenting the hemmed edge.

The shell 11 is completely enclosed within an 15 outer shell 22, which preferably has a curved, substantially continuous top 23, that is engaged and supported by the top of the inner shell along spaced circular lines 24 and 25 to maintain the outer top in its preformed shape. The shell 22 20 has a smooth, depending metallic skirt 26 continuous with the top 23, and may be ornamented in any suitable fashion.

It will be observed that the inner shell is completely formed prior to assembly within the outer 25 shell.

The outer shell has its free edge curled inwardly, as shown at 27, so that when the shells are assembled, as shown in Figure 2, the inner shell is completely enclosed by the outer shell and 30 the curl 27 embraces and engages the roughened hemmed edge 20. This firm engagement is assisted by the resiliency of the outwardly flared portion 17 of the inner shell and the inward curl of the outer shell constantly maintaining the parts in 35 contact and gripping relation.

The curl is formed by bending the free edge of the skirt of the outer shell under the hemmed edge and upwardly and inwardly so that the free 40 edge lies on the interior of the cap as shown at 28.

The inward bend of the portion 28 produces a circumferential groove 29, whereby the edge 30 of the curl will circumferentially engage the roughening 21 on the interior of the hemmed edge.

It will be observed that the roughened hemmed edge is flatly engaged on one side by the adjacent wall of the skirt of the outer shell 22, as at 31, and on the other side by the free edge 30. In 50 this manner, the two shells are firmly clamped together against relative rotation when the cap is turned on a container.

By hemming the lower edge of the inner shell, it is strengthened and, in like manner, the curl produced on the outer shell acts to rigidify the 55

outer shell. When the assembled cap is turned on a container, the hem and curl of the respective shells absorb the strain and prevent distortion of the skirt portions of the shells. The 5 curled edge 27 and the free edge 28 are smooth and continuous and cooperate with the flared portion 17 to form an unobstructed entrant portion for the cap. The flared portion will act to center the cap on the container or neck, and is 10 sufficiently yieldable to accomplish this result without producing strain, such as would tend to distort the smooth continuous appearance of the outer shell.

It will be understood that the inner shell is 15 completely preformed and the outer shell, after the inner shell is inserted therein, will be subjected to the simple operation of forming the curl 27. In some cases, the curl is pressed into engagement with the roughened surfaces of the 20 hemmed edge, but usually the curling of the edge 27 will suffice to produce a rigid contact between the same and the roughened hemmed edge, such that the shells are not rotatable with respect to each other upon turning of the cap.

25 The form of the invention herewith shown and described is merely illustrative of a preferred embodiment, and such changes may be made thereto as fall within the purview of one skilled in the art without departing from the spirit of the

invention and the scope of the appended claims.

I claim:

1. A container closure comprising a shell having a top and a depending skirt, and an inner member overlying said skirt portion and formed with thread engaging portions, the lower edge of said inner member being folded on the body thereof to provide a thickened reinforcing hem, the inner surface of said hemmed portion being roughened to resist rotation thereof within the 10 shell and the lower edge of said skirt on the shell being curled over said hemmed edge and the free edge of said curled over portion grippingly engaging said hem, whereby the inner member is 15 fixedly held within said shell.

2. A container closure comprising a shell having a top and a depending skirt, and an inner member overlying said skirt portion and formed with thread engaging portions, the lower edge of said inner member being folded on the body 20 thereof to provide a thickened reinforcing hem, the inner and outer surfaces of said hemmed portion being roughened to resist rotation thereof within the shell and the lower edge of said skirt on the shell being curled over said hemmed edge 25 and the free edge of said curled over portion grippingly engaging said hem, whereby the inner member is fixedly held within said shell.

GEORGE GOEBEL.
